FIG. 2.

UNITED STATES PATENT OFFICE

1,973,736

RAILWAY TRAFFIC CONTROLLING
SYSTEM

Gilbert C. Whitney, New York, N. Y.

Application August 22, 1931, Serial No. 558,663

16 Claims. (Cl. 246—135)

This invention relates to railway traffic controlling systems in general, more particularly to the operation of power operated track switches, and specifically to a novel means providing release operation of a plurality of such track switches whether operated or controlled electrically or electro-pneumatically and to provide signals in the approach to such track switches and has for an object to increase the safety of traffic over such track switches.

The invention herein disclosed is related to my inventions as disclosed in my Patent No. 1,421,880, issued July 4, 1922, and my co-pending applications, Serial No. 549,148, filed July 7, 1931 and Serial No. 554,893 filed August 3, 1931.

The established practice of the art requires that a means be provided to prevent the operation of a track switch when such operation would be dangerous to a train moving over such switch. This is particularly important where the switch is operated by power. Associated with the track switch there is usually a signal which, when in the clear position, indicates, among other things, that the track switch is in a safe position for the passage of the train. This safety is usually obtained by a system of mechanical locking between the lever which controls the signal and the lever which controls the switch. Coupled with this there is an electric lock on the signal lever controlled by the presence of a train on the track in the approach to the signal and so arranged that this lever, if the signal was cleared for the train, cannot be placed in a position to release the lever controlling the switch while the train occupies said track section in the approach to said signal. Also, there is an electric lock on the switch lever, controlled by the presence of a train on that portion of track in which the track switch is located. These electric locks may be of the gravity drop type or of the forced drop type, in which types the locking element—a plunger, or equivalent—engages with the movable lever element to prevent the lever movement under certain conditions. This arrangement is known as approach locking and detector locking according to its application.

In the arrangement, above referred to, it will be noted that the object sought is to prevent the operation of a track switch and the means used to obtain this effect is applied in an indirect manner, first to the lever controlling the signal and then to the lever controlling the switch. It should also be noted that, as a track switch has two positions so, also, must its controlling lever

have two positions and in order to have the electric lock effective in both positions an obstruction on the lever element is necessary so that the locking element may take effect. Said obstruction introduces a neutral zone in which said locking element cannot take effect to prevent completing an operating circuit at least once.

My invention, disclosed in Patent No. 1,421,880, provides a system of protection embodied in the circuits which control and operate an electrically operated switch mechanism which prevents an operation of the switch with a train on the same portion of track, or in the approach to said portion of track, without regard to the position of the signal lever and, in addition, if the switch mechanism has started when the train approaches, it will complete said mechanism movement and thereby prevent derailment, but when such movement is once completed the switch cannot again be moved until the track section is unoccupied. Also, said invention provides a releasing means arranged to require the positive cooperation of the engineman, or motorman, as will be appreciated.

My co-pending applications Serial Nos. 549,148 and 554,893 disclose novel means of release and include special signal indications at the locations of the releases.

In this application I disclose a novel means of releases and special signal indications at a plurality of locations and releasably controlling a plurality of switch operating mechanisms on a single track or on a plurality of tracks over which any signal may govern. One object of this invention is to provide a system whereby any and all switch operating mechanisms, normally track circuit controlled, may be releasably operated, independent of track circuit control, from selected points, by positive cooperation between the towerman and motorman. The particular advantage of such an arrangement is that in the event of the failure of a track circuit, the signal maintainer can confine his attention to clearing the track circuit trouble instead of operating switch mechanisms by hand—an operation in itself a hazard.

Further objects, purposes and characteristic features of my invention will appear as the description progresses, reference being had to the accompanying drawings showing in a wholly diagrammatic manner, and not in any way in a limiting sense, one form which my invention can assume and, notwithstanding the fact that I have illustrated and will describe this present invention in connection with the same certain form of all-electric operated switch operating mechanism.

system set forth in my prior Patent No. 1,421,880, and my copending applications, it will be clear from the drawings and specification that I have invented a release device and signal means system of broad application equally applicable to the electro-pneumatic type of power operated track switch.

In order that this present invention will be understood more readily I have provided two drawings showing in simplified circuit design outline the essential parts of this invention as used in connection with the all-electrically operated system of my prior Patent No. 1,421,880 and my copending applications, Serial Nos. 549,148 and 554,893.

In the drawings Fig. 1 portrays the invention as applied to two power operated track switches each of which is shown with its own release and signal system and the plurality of units with plurality of releases and signals for the remainder of the power operated track switches shown in Fig. 1 is set forth in Fig. 2.

Referring to Fig. 1: I have shown a three track terminal layout, in part, and consisting of tracks A, B, and C, and wherein track C is further identified as the "east-bound" track and track B is further identified as the "west-bound" track, while track A is a stub-end track further identified as "elevator". Each of these tracks including the cross-over tracks is composed of track rails appropriately insulated, one from the other, to permit the working of a track circuit, in the usual manner, and these tracks are further divided into track sections by means of insulated track rail joints; for example 103, adjacent to switch 12, are insulated track rail joints; similarly this conventional symbol indicates an insulated track rail joint wherever shown in these drawings. As a means of train communication between tracks A, B, and C; crossover tracks including movable track switches 8, 9, 10, 11, 12 and 13 are provided. 6 is a track derail installed to prevent a train moving westbound out of track B while the crossover tracks are set up to permit train movements from tracks A or C to the westbound track. Each of these track switches 8, 9, 10, 11, 12 and 13 and derail 6 are power operated by means of a mechanism SM controlled by their respective levers in an interlocking machine located in the tower, as will be pointed out hereinafter. Appropriately disposed on each track there are signals provided to protect the several switches. These signals are so controlled by the track circuits and levers in the interlocking machine as to prevent the signal being cleared unless the track is unoccupied and the track switches are in proper position and locked, all in the usual manner. Associated with each signal there is a train stopping mechanism, termed an automatic stop, arranged so that parts of such automatic stop will co-act with car-carried related apparatus to stop a train attempting to move past it (and its associated signal) if the automatic stop is in the "stop" position, and if the automatic stop is in the "clear" position such co-action will not be had and the train will not be stopped. In addition to the signal being controlled by track circuits, switches, and levers, as above pointed out, no signal can be cleared unless its associated automatic stop is in the "clear" position. When a train has moved, in part, past a signal (and its associated automatic stop) in the clear position the signal will automatically assume the "stop" position, but the automatic stop will be

retained in the "clear" position to prevent co-action between the stop and the following cars of the same train until the entire train has passed said signal, in the usual manner. The associated automatic stop for signal 5 is identified 5S; similarly 3S, 4S, 15S, 16S and 17S are associated with their respective signals. The automatic stops are operated or controlled by a mechanism, or other appropriate means which includes means for making and breaking contacts whereby to control other circuits according as the automatic stop is in the "clear" or "stop" position, as will be appreciated.

Other than the fact that a contact operated by the respective automatic stops is made use of in this particular disclosure of my invention, no part of the wayside signal and automatic stop system hereinbefore described is a part of my present invention, except that the wayside signal and automatic stop system may be made use of for checking purposes, in the usual manner, as hereinafter pointed out.

As before set forth the three tracks A, B, and C, are insulated and sectionalized to permit the working of the usual track circuit; the track rail portion of track circuit, Sec. 1, extends between signals 3 and 15 on track A; the track rail portion of track circuit, Sec. 3, extends through double slip track switches 9 and 12, on track B; the track rail portion of track circuit, Sec. 4, extends from signal 16 to track circuit, Sec. 3, on track B; the track rail portion of track circuit, Sec. 6, extends from signal 4 to track circuit, Sec. 3, on track B; the track rail portion of track circuit, Sec. 5, extends from signal 5 through track switches 10 and 13, on track C; the track rail portion of track circuit, Sec. 10, extends from signal 17 to track circuit, Sec. 5, on track C; and the track rail portion of track circuit, Sec. 102, is located in the approach to signal 17. Each track circuit includes a source of energy and a track relay connected in series with the respective track rail portions—each track circuit relay being arranged, in the usual manner, so that when no part of the track rail portion of a track circuit is occupied by a train and the circuit is complete the respective track relay will close certain contacts, termed "front" contacts, and when any part of the track rail portion of a track circuit is occupied by a train or the circuit is incomplete the respective track relay will cause said "front" contacts to open and certain contacts, termed "back" contacts, to close. The track rails comprising the crossover tracks are suitably insulated and included in the appropriate track circuit, in the usual manner, so that even a single car train will produce appropriate action on the track circuit installation.

Solely in the interest of simplicity I have not shown the source of energy for any of the track circuits and for the same reason I have shown the track relays for Sec. 102, Sec. 10, and Sec. 5, connected to the respective track rail portions, while the track relays for Sec. 6, Sec. 4, Sec. 3, and Sec. 1, are shown set apart, but it will be understood that, in practice, each track circuit will be constituted and operated, as hereinbefore set forth, in the usual manner. The track circuit relays for Sec. 1, Sec. 3, Sec. 4, Sec. 5, Sec. 6, Sec. 10 and Sec. 102, are hereinafter referred to respectively as 1TR, 3TR, 4TR, 5TR, 6TR, 10TR, and 102TR.

The switch 13 is controlled by lever 13, represented by dotted line and contacts, located in the tower, said contacts being represented in con-

ventional simplified form and operative according to the legend of lever contact operation set forth on the drawings. Lever 13 has a normal and reverse position corresponding to the normal and reverse position of the track switch 13.

In both Figs. 1 and 2 the system is illustrated in the normal condition with all track sections unoccupied, all track relays energized (that is all front contacts made), all track switches set in the normal position, and all levers in the extreme normal position with the appropriate contacts made.

Further, solely in the interest of simplicity, I have omitted the showing of the circuits connected to a source of energy and therefore, it is to be understood that a suitable source of energy (battery) is connected between wires 50 and 51 and between wires 90 and 91.

Associated with each switch controlling circuit I provide a relay (for example WA-13), having two windings, one of which windings termed a pick up coil is controlled by the track relay contacts and the other winding is controlled by current flow in the switch controlling circuit.

The controlling circuit for the pickup coil of relay WA-13 may be traced as follows; from battery (wire 51) to contact 18 on 1TR, wire 19, contact 20 on 3TR, wire 21, contact 22 on 4TR, wire 23, contact 24 on 6TR, wire 25, contact 26 on 5TR, wire 27, contact 28 on 10TR, wire 29, contact 30 on 102TR, wire 31 to the pick up coil of relay WA-13, thence to battery (wire 50). As will be noted, wire 19 has a branch circuit including wire 32 and lever 8N contact to battery (wire 51), so that when lever 8 (and switch 8) is in the normal position WA-13 relay is not controlled by 1TR. Pick up coils for relays WA-10, WA-11, and WA-12 are controlled through this same circuit from battery (wire 51) up to wire 29 where a branch wire 33 to wire 34 is shown extending to WA-10 relay pick up coil, thence to battery (wire 50); from wire 33 to wire 35 to WA-11 relay pick up coil, thence to battery (wire 50); and from wire 33 to wire 36 to WA-12 relay pick up coil, thence to battery (wire 50).

Similarly, the circuit for WA-6, WA-8, and WA-9 relay pick up coils can be traced over the same circuit as above to wire 25 thence via wire 37 to contact 38 on 5TR, wire 39, contact 40 on 10TR, wire 41 to WA-6 relay pick up coil, thence to battery (wire 50); from wire 41, to contact 42 on 1TR, wire 43 to wire 44 to WA-9 relay pick up coil, thence to battery (wire 50); and from wire 43 to wire 45 to WA-8 relay pick up coil, thence to battery (wire 50). Extending between wires 37 and 41 I provide a branch circuit including wires 46 and 47 and lever 12N contact so arranged as to remove the influence of 5TR and 10TR from this circuit when lever 12 (and switch 12) is in the normal position.

The pick up circuits of the WA- relays are arranged to insure that, under ordinary operation, no energy will be applied to a switch operating control circuit when any of the track sections concerned, is occupied, and, from the foregoing it will be evident that the proper TR front contacts must be made if, for example, contact 53 on WA-13 relay is to be closed to complete 13 switch control circuit in regular operation as hereinafter described.

The operation of switch 13 by lever 13 will now be described:— If lever 13 be moved to the reverse operating (indication) position, contact RD

will be made and this sets up the conditions for operating the switch mechanism 13SM, as follows; Current battery (wire 51), contact 53 of WA-13 relay, wire 54 to holding coil of relay WA-13. Thence via wires 55 and 56, lever contact 13RD, wire 57, contact 58 on switch mechanism 13SM, wire 60, to switch motor SM13 to battery (wire 50). The motor, through connection 61, operates the track switch to its reverse position and on completion of the movement opens contact 58 and closes contact 59. This places the circuits in position to operate the track switch back to the normal position again when the lever 13 is moved to the normal operating (indication) position. The operating circuit can be traced as before; from wire 55, lever contact 13NB (now closed), wire 62, contact 59 on switch mechanism 13SM (now closed), wire 63, to switch motor SM13 to battery (wire 50). This circuit is fundamental to electrically controlled track switches whether operated by direct or alternating current and whether operated by one or more sources of power.

In operation, it should be understood that all track switch controlling levers have a preliminary movement limited by a system of indication locking (not shown but commonly used and well known in this type of interlocking system) which prevents the respective lever from making up the extreme contact N or R, as the case may be, unless and until the corresponding switch operating mechanism has completed its movement, by bolt locking the switch, and indicating the same.

As pointed out in my Patent No. 1,421,880, the novelty in the use of relay WA-13 resides in its maintaining the operating circuit if the switch motor SM13 is drawing current from battery (wires 50-51) and preventing the operating circuit being established if the motor SM13 is not drawing current from said battery (wires 50-51), and any track relay contact is open. The switch operating control wire 62 also receives energy from battery (wire 51) through lever contact 13N and wire 65. Contact 13R and wire 64 to wire 57 provides a similar control when lever 13 is in the reverse position, as will be appreciated.

As above stated, lever 13 has a preliminary movement which prevents lever contacts 13N and 13R being made unless certain conditions have been set up, and therefore, while the lever 13 moves between the normal operating (indication) and reverse operating (indication) positions, lever contacts 13N and 13R cannot be closed, and thus when lever 13 is in an operating position the operating current for SM13 must be received through contact 53 on WA-13 relay, which requires, except as hereinafter pointed out, that the pick up coil of WA-13 relay must be energized if the operating circuit is to be established.

It has been shown that the operating current for the switch mechanism 13SM is taken in series through the holding coil of safety relay WA-13 and through contact 53 when this relay is energized. The following conditions, therefore, result: When the lever 13 is placed in either N or R position, the operating circuit of switch mechanism 13SM is not under the influence of track circuit control; when the lever 13 is not placed in either N or R position the operating circuit of switch mechanism 13SM is under the control of WA-13 relay; when the switch mechanism is drawing current relay WA-13 is maintained energized by the holding coil; when relay WA-13

is deenergized the switch cannot be operated by power. Attention is here directed to the fact that contact 53 does not open while the switch mechanism is drawing current; no provision, therefore, is necessary to guard against arcing of the contact even when this circuit is operated on high voltage. Attention is also directed to the fact that I may separate the functions of relay WA-13 into two or more relays with the same ultimate result as I have obtained with but one relay. By virtue of contact 53, relay WA-13 becomes a stick relay.

The application of this system will be understood by considering the approach of a train 15 eastbound, that is, in the direction of the arrow on track C. When signal 17 is clear, the route is established for the through movement of the train and when the train is on Sec. 102, Sec. 10, or Sec. 5, a movement of the lever 13 cannot 20 produce a corresponding movement of the switch 13 since the pick up coil circuit of relay WA-13 is opened by the track relays and the movement of lever 13 opening the N and R contacts prevents current being supplied directly from wire 25 51 over wires 57 or 62 to the switch operating mechanism. In view of the track circuit control, contact 53 will be open controlling the current to the switch operating motor SM13. Now, if the switch movement is partially made when the 30 train enters Sec. 102, although the pick up coil circuit of relay WA-13 will be deenergized, the holding coil of this relay is energized until the operating circuit is opened at contacts 58 or 59 upon completion of the movement, when it 35 becomes deenergized. Sec. 102 is of such length that a train at maximum speed passing over it will consume a greater time interval than that necessary for the complete operation of the track switch movement. Where necessary, an additional section of track may be arranged to control the circuit of relay WA-13 for this purpose. By this arrangement switch 13 will be in position and locked before the train enters upon Sec. 10 and it cannot again be moved until the 40 train passes off this section, except as hereinafter pointed out. This system, therefore, becomes a substitute for approach locking, provides track circuit control of the switch mechanism, and insures a completed movement of the switch independently of the track circuit control, all in the most direct manner and independent of the position or subsequent movement of the signal or its controlling lever and, also, independent of the position of the switch mechanism or the 50 position or subsequent movement of its controlling lever.

In practice it frequently happens that the route cannot be established for a train approaching signal 17 and the signal 17 remains in the stop position. In dense traffic, for instance, a previous train may not have cleared the route when the following train enters upon Sec. 102; signal 17 and automatic stop 17S are used to stop said following train. It occasionally happens that a train will over-run the signal, even though the train brakes have been applied by co-action with stop 17S, or a train may pass signal 17 (with stop 17S not in co-active working order) in the stop position on the instruction of a hand signal or flag. Without the protection afforded by the invention of my prior Patent No. 1,421,880 under these conditions the switch lever 13 is free to be moved and to operate the switch mechanism until the train enters Sec. 10

when an electric detector lock, not shown in the drawings but commonly used in practice, restricts the movement of the lever. Now, if the lever 13 is not placed in a position, whereby the plunger of the electric detector lock can take effect on the movable lever, before the train enters Sec. 10, it is apparent that the lever 13 may be operated to cause an operation of the switch mechanism at any time. With the invention of my prior Patent No. 1,421,880, this cannot occur as the track circuits control the switch operating current at all times, except when the switch motor is drawing current, and regardless of the electric detector lever locks.

In the ordinary course of operation, it is, of course, necessary at times to be able to operate the switch 13 when a train is stopped at signal 17 and, therefore, occupying Sec. 102. I provide for this by requiring the positive cooperation of the engineman or motorman together with the 95 operation of lever 13 to set up the conditions for operating the switch mechanism 13SM.

As shown in Fig. 1, I have provided a release device located at signal 17 and have arranged and included this release device in co-operative 100 control of the switch mechanism 13SM in its operating circuit which may be traced as follows: From wire 54 on relay WA-13, to wire 82a, to lever contact 13BD thence via wire 82 to relay 83 and wire 84 to battery (wire 51). Also I 105 provide a shunting circuit including wires 95 and 97 and normally open manually operable self-restoring contact 98 and so arranged that when contact 98 is closed a low resistance shunt is established around relay 83. Also, I have provided a lamp signal circuit including a source of energy (wires 90-91), lamp signal 89 and contact 86 on relay 83. When relay 83 is energized to close contact 86 this lamp signal circuit will be complete and the lamp lighted, as will be appreciated. I have also provided a checking circuit including wires 99, 100, 101 and contact 87 on relay 83 and normally closed self-restoring contact 102 manually operable with contact 98 by operating member 94 to insure that contact 110 98 and relay 83, after operation, are restored to the normally open position. This checking circuit may be included in any suitable signal or automatic stop control, as will be appreciated.

When the train is standing at signal 17, 102TR 125 contact 30 being open and, therefore, WA-13 relay contact 53 being open and it is desired to operate switch 13 to the reverse position to route the train to track B, the towerman moves lever 13 to the reverse operating (indication) position. 130 As soon as the lever 13 contact RD is made, a circuit is established which may be traced as follows: from battery (wire 51) thence via wire 84, relay 83, wire 82, lever 13 contact BD (now closed), wire 82a, wire 54, holding coil on relay WA-13, 135 wires 55 and 56, lever 13 contact RD (now closed), wire 57, contact 53 on switch mechanism 13SM, wire 60 to switch motor SM13, to battery (wire 50). Relay 83 has a resistance such that current flow in this circuit, just traced, is not sufficient 140 to energize relay WA-13 to close contact 53 or to start the switch mechanism in operation, but is sufficient to close relay 83 contact 86 to light lamp signal 89 and to open relay 83 contact 87. Current flow in this switch operating circuit is 145 indicated to the motorman (train at signal 17) by the lighting of lamp 89 and, by rule or design of the signal associated therewith, the motorman is instructed to operate the release device 94 and, with the closing of contact 98, a low resist- 150

- ance shunt circuit is established around relay 83. When this shunt circuit is established, increased current, sufficient to operate stick relay WA-13 to close contact 53, flows in the circuit. With 5 the closing of contact 53 the functioning of the switch operating system is the same, as previously explained, until contact 58 on switch operating mechanism 13SM opens at the completion of the movement, which opens the operating circuit 10 thus deenergizing relay WA-13 and contact 53 opens. With the closing of contact 98 on release device 94, relay 83 is deenergized, contact 86 opens and lamp signal 89 is extinguished thus standing as an indication to the motorman that 15 the switch operating mechanism has begun to operate. After contact 53 opens, switch operating mechanism 13SM cannot be energized as long as the pick up coil circuit of relay WA-13 is open, unless lever 13 is put in proper position and 20 the same positive cooperation of the motorman obtained, as before. After the completion of an operation thus performed the towerman may complete the movement of lever 13 and clear signal 17 or the motorman may proceed by instruction or hand signal but the train being stopped cannot accelerate to over-run the switch points before the switch movement is completed. 25
- In connection with WA-13 relay, I have provided a circuit including battery (wire 51), contact 68 on relay WA-13, wire 69, relay indicator lamp 70 to the battery (wire 50). Contact 68 is closed and this circuit completed with lamp 70 lighted whenever relay WA-13 is deenergized. Therefore, whenever the pick up coil circuit of 30 relay WA-13 is open relay indicator lamp 70 will be lighted indicating to the towerman that the switch cannot be moved by power, except under the release operation above explained. Now, when relay WA-13 is energized by the closing 35 of release device contact 98, lamp 70 will be extinguished until the switch mechanism 13SM contact 58 opens at which time the lamp 70 will be lighted again, and with lever 13 in an operating position this cycle of lamp illumination operation indicates to the towerman that the release device 40 has been operated and that the switch mechanism 13SM has completed its movement. If the lever 13 be not in an operating position, lamp 70 lighted indicates that some part of a route 45 in which switch 13 is included, is occupied or some circuit incomplete and lamp 70 not lighted indicates that no part of a route in which switch 13 is included, is occupied by a train. 50
- It should be noted that in the event of the pick up circuit of relay WA-13 being completed by the closing of any track relay contact, contact 53 on relay WA-13 will close and (lever 13 being in an operating position) the switch movement 55 will be started just the same as though release contact 98 had been operated—and, obviously, under these conditions lamps 89 and 70 will become extinguished removing the indication to operate the release device 94 and, also, informing the towerman that the switch operating mechanism 60 has begun to operate.
- The operation of switch 10 by lever 10 is substantially the same as has been described hereinbefore for the operation of switch 13 by lever 13 insofar as the ordinary operation is concerned but differs in respect to release device operation as will be pointed out hereinafter. In view of the foregoing it is believed that expanding the drawings and specification to show reference numbers 65 and description as to the ordinary operation of switch 10 by lever 10 is not necessary to a complete understanding of this invention. It will be noted that no approach track circuit is provided in the approach to signal 5 and that the pick up coil of relay WA-10 is not controlled by 102TR. 70
- As shown in Fig. 1, I have provided a release device located at signal 5 and have arranged and included this release device in cooperative control of the switch mechanism 10SM in its operating circuit which may be traced as follows: From wire 154 on relay WA-10, to wire 182a, to lever contact 10BD, thence via wire 182b, to contact controlled by automatic stop mechanism 5S and closed only when 5S is in the stop position, thence to wire 182 to relay 183, thence via wire 184 to battery (wire 51). Except that automatic stop 75 5S must be in the stop position the functioning of the releasing system for switch 10 from the location of signal 5 is similar in all respects to the functioning of the releasing system for switch 13 from signal location 17, hereinbefore explained at length. In view of the above it is believed that further description is not necessary to a complete understanding of the release circuit operation of switch 10 from signal 5 location. 80
- In the further interest of simplicity in the drawings I have not shown the complete switch control and operating circuits for the ordinary operation of switches 8, 9, 11, and 12 and derail 6 by their respective levers which in practice will be precisely 85 similar to the control of switch 13 by lever 13, except as to the control of the pick up coils of the respective WA relays, hereinbefore described, and except as to the respective releasing circuits hereinafter set forth in the description of Fig. 2. 90
- Now, it is apparent that every track switch in this track layout may be operated over as a facing point switch, that is, a track switch, which if moved while a train is moving over it, will derail the train and, therefore, a release device, constituted and connected similarly to that at signal 17, must be located at every signal. Similarly, it should be apparent that every track switch in this track layout may be operated over as a trailing switch, that is a track switch arranged to permit train movement from either of two tracks to one track. For example, switch 12 is a trailing switch insofar as eastbound train movements are concerned while the same switch 12 is a facing point switch insofar as westbound train movements are concerned. Similarly, it should be clear that in any two switches, forming a cross-over track, one switch will be facing point and the other switch will be trailing point with respect to train movement in one direction and for train movement in the opposite direction the former switch will be trailing point and the latter switch will be facing point. Therefore, it is permissible to operate the two switches of a crossover track simultaneously, 100 for ordinary operations, by one lever. While this situation simplifies and speeds up the operation of an interlocking machine, the release operation of one switch of a cross-over must be carried out independently of the other switch of said crossover, for the reason, for example, that release operation of both cross-over switches 10 and 11 from the location of signal 16 would result in switch 10 being thrown under a train moving westbound over switch 10 in the normal position. In 105 the event that no train was occupying section 5, release operation of switch 10 from location 16 not only would be permissible but actually required in case no train motorman was available to release switch 10 from signal 5 location on track C. In 110 115

Fig. 2, I have illustrated the application of my invention to the solution of this problem.

Referring to Fig. 2: At the top of the drawing I have shown the releasing circuit control of 5 WA-13 relay controlling switch 13 and at the bottom of the drawing I have shown the releasing circuit control of WA-10 relay, all of which, including character references, is the same as shown in Fig. 1, and the description hereinbefore set 10 forth applies. Similarly, the releasing circuit for derail 6 and switch 12, controlled direct from the release device located at signal 4 over wire 6-12-82 including a contact made only in the stop position of automatic stop 4S; the releasing 15 circuit for switch 8 controlled direct from the release devices located at signal 15 and signal 3 over wire 8-82 including a contact both made only in the stop position of automatic stops 15S and 3S; and the releasing circuit for switch 9 and 20 switch 11 controlled direct from the release device located at signal 16 over wire 9-11-82 including a contact made only in the stop position of automatic stop 16S; are shown in Fig. 2. In view of the above it is apparent that derail 6 and 25 switches 8, 9, 10, 11, 12, and 13 may be release operated from selected locations independently of track circuit control, the direct release location being placed with respect to train movement which operates over the respective switches as facing 30 point switches, except as to switch 8 and release location 15.

Since two switches, one of which is facing point and the other is trailing point, are involved the means required to release operate the 35 trailing point switch must be track circuit controlled and to accomplish this I provide a circuit, termed a bus line, connecting all of the release operating wires 82, 6-12-82, and so on, which bus line circuit may be traced as follows: From 40 wire 82 via wire GW, contact on 10TR, wire GW1, contact on 5TR, wire GW2, contact on 6TR, wire GW3, contact on 3TR, wire GW4, connecting to wire 6-12-82 and continuing to contact on 3TR, wire GW5, contact on 6TR, wire 45 GW6, contact on 3TR, wire GW7, contact on 4TR, wire GW8, connecting to wire 9-11-82 and continuing to contact on 4TR, wire GW9, contact on 3TR, wire GW10, contact on 5TR, wire GW11, and connecting to wire 182. This bus 50 line has a branch bus line from wire GW5 as wire GW12, to contact on 6TR, wire GW13, contact on 1TR, and wire GW14 connected to wire 8-82.

This bus line above traced, while always at 55 the potential of battery (wire 51) via of relays windings 83, 183, etc.; may also have the same potential impressed via the WA relay contacts 53, 153, etc., but only when a switch operating mechanism is drawing current; or when the pick up 60 coil of a WA relay is energized closing the respective 53 contact providing the respective lever is in an operating position. Current may flow in this bus line only when one or more levers are put in an operating position and the respective 65 WA relay pick up coil circuit is open (at a TR contact or otherwise) under which condition current will flow from battery (wire 51) through the respective direct releasing circuit including the respective 83-183 etc., relays; and from battery 70 (wire 51) through any and all other releasing circuits including 83-183 etc., relays according as the bus line circuit including TR contacts, is complete. Current flow through the 83-183 etc., relays closes the respective contacts 86 causing 75 the display of the release signals 89 etc.,

at the respective locations and this condition will remain until either the pick up coil circuits of the WA relays are completed or a manually operated release device 94-194 etc., is operated.

As before stated, Fig. 2 illustrates a plurality of direct releasing circuit and signal combinations including those shown in Fig. 1 for switches 13 and 10, which combinations have been interconnected by a track-circuit-controlled bus-line to provide release operation of a switch mechanism from one of a plurality of releasing locations as well as to provide release operation of a plurality of switch mechanisms from a single release location. As will be observed from Fig. 2, all of the switch operating mechanisms may be 80 directly release operated from at least one location. The indirect or plural release operation will be clear from the following:—It will be noted that the normal track circuit control (pick up coils) of relays WA-6 (for the derail mechanism 6) and WA-12 (for the switch operating mechanism 12) includes contacts on track circuit relays 3TR, 4TR, and 6TR. In the event that section 4 is occupied by a train, or the track relay 4TR is deenergized due to track circuit failure, the movement of either controlling lever 6, or lever 12, to the operating position would not produce a corresponding derail or switch mechanism movement for the reason that the 53 contact on the respective WA relays would be open. 90 Now, if the automatic stop 4S contact is closed (indicating that the stop is set in the tripping position) the circuit of the derail and switch mechanisms is extended from the holding coils of the relays WA-6 and WA-12 through BD 110 contacts (now closed) on the respective levers, via wire 6-12-82 to the (83) relay located at signal 4 where, due to relay (83) being energized, a signal (89) would appear, as hereinbefore explained in connection with the release operation 115 of switch 13. In the event that there is no train in station track B there would be no motorman response to operate the push button (94) at signal 4 location. By means of the bus-line connected to wire 6-12-82 means are provided 120 whereby a branch circuit traced through contacts on 3TR, 6TR, 5TR, and 10TR extends, via wire 82, to the releasing means at signal 17 location where relay 83 would be energized, thus displaying release signal 89; and a branch circuit 125 also may be traced from wire 6-12-82 thence over contacts on 3TR, 6TR, and 1TR to wire 8-82 to the releasing means at signal 15 and signal 3 locations where the respective (83) relays would be energized, thus displaying respective (89) signals. At any one of these 130 locations, at signals 17, 15, 4, or 3, the releasing button (94) may be operated thus shunting the respective relay and permitting sufficient current to flow to energize WA-6 and WA-12 relays to close the respective (53) contacts whereupon the individual switch mechanisms function, as explained hereinbefore. It will be appreciated that the shutting of one (83) relay acts to shunt all (83) relays and, therefore, all (89) signals 135 become extinguished. In view of the BD contacts being included in the circuits as shown it should be apparent that the respective lever must be in an operating position in order to release 140 operate the respective switch mechanism and, therefore, the release operation, above described, applies to either or both switch mechanism 12 or derail mechanism 6. Contacts BD on the respective levers also provide the means whereby, for example, with lever 13 in the full normal 145 150

- or full reverse position, energy (battery wire 51) via contacts N and R on lever 13 is prevented from backing around through the holding coil of relay WA-13 thence via the bus-line contacts 5 to by-pass the release operation control of other WA relays. In the event of track relay 3TR or 6TR being deenergized, the release operation of switch 12 and derail 6 can be made only from the facing point direction at signal 4 location, 10 due to the bus-line contacts 3TR and 6TR being open on both branch circuits of wire 6-12-82. 15 As further description of Fig. 2: Assume that section 6 is occupied by a train, or that 6TR is deenergized on account of track circuit failure, and it is desired to operate switch 10: Placing lever 10 in an operating position would not result in energy flow to 10SM because the 153 contact on WA-10 relay would be open. With lever 10 in an operating position and automatic 20 stop 5S in a tripping position the circuit of 10SM will be extended over wire 182a, lever contact 10BD, wire 182b, contact on 5S (now closed), to wire 182, to relay 183, thence over wire 184 to battery (wire 51), and current flow in this 25 circuit will result in energizing said relay 183 to display release signal (89) at signal 5 location—in substance—the direct releasing circuit is set up. By means of the bus-line GW11 wire connection to wire 182, a branch releasing circuit 30 is also extended over 5TR, 3TR, and 4TR to wire 9-11-82 and thence via relay (83) to battery (wire 51), and energy flow in this branch circuit will result in the energizing of said relay (83) to display the release signal (89) at 35 signal location 16. The operation of the motor-man's release button 194 to shunt relay 183 at signal location 5, or the operation of the motor-man's release button at signal location 16, will result in increased current flow in the switch 40 mechanism circuit for 10SM, as hereinbefore explained, and contact 153 on WA-10 relay will be closed, thus resulting in the release operation of 10SM. 45 The closing of the manually operated contact 98-198 etc., first operated will cause current flow through the holding coils of all WA relays included in a completed direct releasing circuit (or circuit made up through the bus line) where-in the respective switch operating circuit, includ- 50 ing lever, automatic stop, and mechanism, contacts, is complete and the pick up coil circuits of the respective WA relays are open. Also, the closing of the manually operated contact 98-198 etc., first operated extinguishes all release signals 89 etc. The resistance of relays 83-183 etc., is selected such that current flow through all such relays connected in multiple is not sufficient to energize the holding coil of a single WA relay 55 to close its front contacts. 60 From the above description it should be clear that any number of single direct releasing circuits, as illustrated in Fig. 1 and described in connection with switch 13 and switch 10, may be joined by bus line including TR contacts ap- 65 propriately arranged. 70 Contacts N and R on the respective levers may be omitted entirely and the system will function properly by the pick up coils of the respective WA relays controlling through the track circuit relays only. An advantage secured by having the potential of battery (wire 51) impressed on the switch operating circuits when the lever is in an N or R position is that if a switch should be misplaced and a controlling track relay open, conditions will be established 75 automatically, by means within the switch operating mechanism (not shown but standard and commonly used in this type of apparatus) to move the switch into a position corresponding with its controlling lever. In the event that said N and R contacts are omitted I prefer to use an electric release type of mechanical brake applied to the switch operating mechanism and included in the switch operating control circuit to prevent the switch mechanism being misplaced. 80 Furthermore, one or more relays controlled by a lever or other control may be substituted for the direct lever control illustrated in this disclosure of my invention. 85 The track circuit control of the switch mechanism is always effective to control the operating current except for the interval during which the mechanism is drawing current. This is a form of protection superior to that indirectly obtained from track circuit controlled locks applied to 90 levers. 95 I desire to direct special attention to the fact that since this releasing and signal system is connected in the energy supply to levers controlling the switch operating mechanisms it is 100 equally applicable to the electro-pneumatic power operated switch operating system. 105 The above rather specific description of one form of my invention, is given solely by way of illustration, and is not intended, in any manner whatsoever, in a limiting sense. Obviously my invention can assume many different physical forms, and is susceptible of numerous modifications, and all such forms and modifications are intended to be included, in this application, as 110 come within the scope of the appended claims. 115 Having described my invention, I now claim: 1. In a railway traffic controlling system including track circuit control of power operated track switch operating mechanisms, a releasing circuit including a plurality of normally open manually operable contacts connected in multiple, said releasing circuit including a lever contact made only in an operating position of said lever, and a plurality of signals to indicate that a manually operable contact is to be operated, said manually operable contact nullifying said track circuit control of said switch operating mechanism. 120 2. In a railway traffic controlling system including track circuit control of power operated track switch operating mechanisms, a releasing circuit including a plurality of normally open manually operable contacts connected in multiple, said releasing circuit including a lever contact made only in an operating position of said lever, and a plurality of signals to indicate that a manually operable contact is to be operated, said manually operable contact nullifying said track circuit control of said switch operating mechanism. 125 3. In a railway traffic controlling system including track circuit control of power operated track switch operating mechanisms, a plurality of releasing circuits, each of said circuits including a lever contact made only in an operating position of said lever, a normally open manually operable contact, and a signal to indicate that said manually operable contact is to be operated, said manually operable contact controlling all of said releasing circuits to nullify said track circuit control of said switch operating mechanisms, said manually operable contact extinguishing said signal. 130 4. In a railway traffic controlling system in- 135 140 145 150

- cluding track circuit control of power operated track switch operating mechanisms, a plurality of releasing circuits, each of said circuits including a lever contact made only in an operating position of said lever, a plurality of normally open manually operable contacts, a signal associated with each of said manually operable contacts to indicate that said contact is to be operated, and a bus line including track circuit relay contacts 5 joining all of said releasing circuits.

5. In a railway traffic controlling system including track circuit control of power operated track switch operating mechanisms, a plurality of releasing circuits, each of said circuits including a lever contact made only in an operating position of said lever, each of said releasing circuits controlled directly from at least one normally open manually operable contact, each of said releasing circuits controlled from another normally open manually operable contact over a circuit 10 including a track circuit relay contact, and a signal controlled by each of said releasing circuits to indicate that a normally open manually operable contact is to be operated, said releasing circuits controlling circuits for said mechanisms independently of said track circuit control.

6. In a railway traffic controlling system including track circuit control of power operated track switch operating mechanisms, a releasing circuit including a lever contact made only in an operating position of said lever, a normally open manually operable contact controlling said releasing circuit in combination with said lever contact, and a signal to indicate that said manually operable contact is to be operated, said signal controlled by said lever contact, said releasing circuit controlling the circuit of a switch operating mechanism independently of said track circuit control.

7. In a railway traffic controlling system including track circuit control of power operated track switch operating mechanisms, a releasing circuit including a lever contact made only in an operating position of said lever, a normally open manually operable contact controlling said releasing circuit in combination with said lever contact, said releasing circuit included in the operating circuit of a switch operating mechanism and controlling said mechanism independently of said track circuit control.

8. In a railway traffic controlling system including track circuit control of power operated track switch operating mechanisms, a signal means, said means controlled by a circuit including a lever contact made only in an operating position of said lever, and a shunt circuit including a normally open manually operable contact, said manually operable contact nullifying said track circuit control of a plurality of switch operating mechanisms.

9. In a railway traffic controlling system including track circuit control of a power operated track switch operating mechanism, a lever, said lever selectively controlling said mechanism, a signal means, said means controlled by a circuit including a contact made only in an operating position of said lever and by a contact on the wayside apparatus of a train stopping device, and a shunt circuit including a normally open manually operable contact, said manually operable contact nullifying said track circuit control of said switch operating mechanism.

10. In a railway traffic controlling system including a power operated track switch operating mechanism, a detector track circuit, said track

circuit controlling said mechanism, wayside apparatus of a train stopping device, a releasing circuit including a normally open manually operable contact and a contact made in the stopping position controlled by said device, and a signal to indicate that said manually operable contact is to be operated, said signal and said manually operable contact remotely located, said releasing circuit nullifying said track circuit control of said mechanism.

11. In a railway traffic controlling system including track circuit control of a power operated track switch operating mechanism, wayside apparatus of a train stopping device, a releasing circuit including a normally open manually operable contact and a contact made in the stopping position controlled by said device, said releasing circuit nullifying said track circuit control of said mechanism, and a signal to indicate that said manually operable contact is to be operated.

12. In a railway traffic controlling system including track circuit control of a power operated track switch operating mechanism, a circuit controlling said mechanism, said circuit controlled by a lever, a relay having an operating coil controlled by said track circuit and a holding coil included in the circuit of said mechanism, said relay at times controlling said circuit, and a circuit established by said lever in its extreme positions to energize said mechanism circuit independently of said relay.

13. In a railway traffic controlling system including track circuit control of a power operated track switch operating mechanism, a circuit controlling said mechanism, said circuit controlled by a lever and by said track circuit, a circuit established by said lever in its extreme positions to energize said mechanism circuit independently of said track circuit, a relay and circuit controlled by said lever in an operating position when said track circuit is occupied, a signal, said relay controlling said signal, and a circuit including a manually operable contact, said circuit and contact for controlling said relay and nullifying said track circuit control of said mechanism circuit.

14. In a railway traffic controlling system including track circuit control of a power operated track switch operating mechanism, a circuit controlling said mechanism, said circuit controlled by a lever and by said track circuit, a circuit established by said lever in its extreme positions to energize said mechanism circuit independently of said track circuit, a relay and circuit controlled by said lever in an operating position when said track circuit is occupied, a signal, said relay controlling said signal, a circuit including a contact on a manually operable releasing device, said circuit and contact for controlling said relay and nullifying said track circuit control of said mechanism circuit, and a checking circuit including a normally closed contact on said device and a normally closed contact on said relay.

15. In a railway traffic controlling system including track circuit control of a power operated track switch operating mechanism, a circuit controlling said mechanism, said circuit controlled by a lever and by said track circuit, wayside apparatus of a train stopping device, a circuit including a relay and a contact controlled by said train stopping device controlled by said lever in an operating position when said track circuit is occupied, a signal, said relay controlling said signal, and a circuit including a manually operable contact, the last mentioned circuit for con-

trolling said relay and nullifying said track circuit control of said mechanism circuit.

16. In a railway traffic controlling system including track circuit control of a power operated track switch operating mechanism, a circuit controlling said mechanism, said circuit controlled by a lever and by said track circuit, wayside apparatus of a train stopping device, a circuit including a relay and a contact controlled by said

train stopping device controlled by said lever in an operating position when said track circuit is occupied, a signal, said relay controlling said signal, and a circuit including a manually operable contact and a track relay contact for controlling said relay and for nullifying said track circuit control of said mechanism circuit.
